UNITED STATES PATENT OFFICE.

HARRY M. BURR, OF MIDDLETOWN, AND GEORGE J. INGRAHAM, OF WEST HARTFORD, CONNECTICUT, ASSIGNORS TO THE OMC MFG. CO., OF MIDDLETOWN, CONNECTICUT, A CORPORATION.

INSULATING, WATERPROOF SOLE FOR USE ON BOOTS AND SHOES.

1,347,775.

Specification of Letters Patent. Patented July 27, 1920.

Application filed July 2, 1919. Serial No. 308,160.

To all whom it may concern:

Be it known that we, HARRY M. BURR and GEORGE J. INGRAHAM, citizens of the United States, residing, respectively, at 5 Middletown, in the county of Middlesex, and at West Hartford, in the county of Hartford, and State of Connecticut, have invented a new and useful Improvement in Insulating, Waterproof Soles for Use on 10 Boots and Shoes; and we do hereby declare the following, when taken in connection with the accompanying drawings and the characters of reference marked thereon, to be a full, clear, and exact description of the 15 same, and which said drawings constitute part of this application, and represent, in—

Figure 1 a plan view of an insulating, waterproof rubber sole embodying our invention.

20 Fig. 2 an enlarged view thereof in transverse section on the line 2—2 of Fig. 1.

Our invention relates to an improved insulating, waterproof sole for use on boots and shoes, either by the manufacturer or by 25 repairers, the object being to provide a light and durable sole characterized by its ability to protect the foot from heat and cold.

With these ends in view, our invention 30 consists in a two-part insulating waterproof sole consisting of a lower portion or wearing layer, and a separately fabricated upper portion or insulating layer incorporated with the upper face of the lower portion and having a component of insulating material such as hair.

Our invention further consists in an insulating, waterproof sole composed of a waterproof wearing portion and an insulating 40 portion, the two portions being independently fabricated and united by incorporation, and the insulating portion containing animal hair and a binder.

Our invention further consists in certain 45 details and features as will be hereinafter described and pointed out in the claims.

In carrying out our invention, we preferably produce by the process commonly known as "sheeting," the sheets from which 50 the lower or wearing portions of the soles are cut, these sheets consisting of rubber or other vulcanizable gum combined with asbestos fiber which by preference is arranged transversely to the axis of the fin-

ished soles. In place of rubber alone, we 55 may employ rubber combined with a vulcanizable gum, or some other vulcanizable gum alone or in combination, and in place of asbestos, we may employ mineral wool.

The insulating portion of the sole is separately fabricated by the same "sheeting" process. For the insulating component of this portion of our improved sole, we preferably employ animal hair, such as goat hair or calf hair, because it is light and 60 non-absorbent, because it is not disintegrated by the heat to which it is subjected during the vulcanization of the binder, and because it even appears to assist the vulcanizing process. However, in place of animal hair, we may employ silk or cotton, or 65 hemp, or other vegetable fiber. As a binder for the hair or fiber, we employ rubber or some compound containing rubber. Thus the rubber may be diluted with other gums, 70 such as balata gum or gutta percha.

The thickness of the respective sheets fabricated for the upper and lower portions of the soles, will depend, of course, upon the use to which they are to be put, such as 80 the character of the boots and shoes on which they are to be used, climate, etc., etc.

The two sheets having been produced as described, are superimposed one upon the other and united with the resultant production of a composite sheet having distinctive upper and lower portions adhered together but remaining segregated, the segregated sheets being united by the softening and flowing of the rubber or other binder used in 85 their independent fabrication. Out of these composite sheets, soles are cut of the required size, the cutting being done so that the fibers in the relatively thick wearing portion are arranged transversely, and therefore lengthwise with respect to the axes of the soles, since in this manner the soles are made more flexible lengthwise than crosswise, it being desirable that the soles shall be flexible lengthwise, but as rigid as possible crosswise.

After the soles have been cut from the composite sheets, they are cured by being placed in suitable molds in which they are subjected to heat and pressure, the curing 105 process being the same as commonly employed for articles containing a component of rubber. The rubber and asbestos com-

ponents of the lower portions of the soles, and the hair and rubber components of the upper portions of the soles are, of course, mixed with suitable vulcanizing agents preparatory to "sheeting." If desired the composite sheets may be vulcanized before the soles are cut out instead of cutting out the soles from the raw sheets and then vulcanizing the soles as above described.

10 Our improved sole, in addition to furnishing the waterproofing qualities of rubber soles as heretofore used, provides for insulating the foot from heat and cold which are transmitted through the ordinary rubber soles and constitute an objection to their use. At the same time, our improved sole is not made appreciably heavier or bulkier than the ordinary sole, while greatly increased in efficiency and comfort.

15 We claim:—

1. As a new article of manufacture, an insulating waterproof sole for boots and shoes, comprising a lower or wearing portion and an upper or insulating portion, these portions being separately fabricated and united, and the lower portion containing rubber and asbestos fiber which latter is arranged transversely, or substantially transversely, to the axis of the sole, and the upper portion containing a component of insulating material.

2. A new article of manufacture, an insulating waterproof sole for boots and shoes,

consisting of an upper insulating portion and a relatively thicker lower or wearing portion, the said portions being separately 35 fabricated and subsequently united and incorporated, and the upper portion containing a non-absorbent animal fiber and a binder therefor.

3. As a new article of manufacture, an insulating waterproof sole for boots and shoes, consisting of a separately fabricated lower portion and relatively thin separately fabricated upper portion, the said portions being united and incorporated, and the upper 45 portion containing animal hair intermingled with a vulcanizable gum as a binder.

4. As a new article of manufacture, an insulating waterproof sole for boots or shoes, consisting of an upper or insulating portion 50 and a separately fabricated lower or wearing portion, united and incorporated by heat and pressure, the upper portion containing animal hair and rubber, and the lower portion containing rubber and mineral fiber.

55 In testimony whereof we have signed this specification in the presence of two subscribing witnesses.

HARRY M. BURR.
GEORGE J. INGRAHAM.
